UNITED STATES PATENT OFFICE.

JOHN R. FORTUNE AND HAROLD S. WELLS, OF DETROIT, MICHIGAN; ASSIGNEES TO MURPHY IRON WORKS, OF DETROIT, MICHIGAN, A CORPORATION OF MICHIGAN.

REFUSE-BURNER.

981,254.

Specification of Letters Patent. Patented Jan. 10, 1911.

Application filed October 27, 1909. Serial No. 524,981.

To all whom it may concern:

Be it known that we, JOHN R. FORTUNE and HAROLD S. WELLS, citizens of the United States of America, residing at Detroit, in the county of Wayne and State of Michigan, have invented certain new and useful Improvements in Refuse-Burners, of which the following is a specification, reference being had therein to the accompanying drawings.

10 This invention relates to a refuse burning furnace and its object is to provide a furnace for the purpose so arranged and constructed that a thin layer of refuse material having an extended area, will be automatically fed to the furnace grates in such a manner that it will be stirred or mixed, thoroughly dried and partially coked by the heat of the products of combustion passing over it before reaching the grates, the operation 15 of the feeding mechanism being adapted to be regulated according to the kind of material composing the refuse being burned.

20 A further object is to provide certain other new and useful features in the construction, arrangement and combination of parts, all as hereinafter more fully described, reference being had to the accompanying drawings in which,

25 Figure 1 is a transverse vertical section through a furnace embodying the invention; Fig. 2 a longitudinal section of the same substantially on the line $x-x$ of Fig. 1; Fig. 3 is a perspective detail of three of the feed bars; and Fig. 4 is a similar view 30 of one bar with part of the pusher blocks removed and the other partly broken away to show the construction.

35 As shown in the drawings, 1 and 2 are the outer side walls of a furnace and 3 the ash pit at the bottom of the fire chamber 4 over which chamber springs an arch 5 curved longitudinally of the fire chamber and extending laterally from the wall 1. Over the arch 5 at a distance above the 40 same is a second arch 6 which springs from the side wall 1 and extends across to a suitable arch plate 7 forming one side of the throat of a hopper 8, the opposite side of the hopper being formed by the side wall 2 and an inwardly and downwardly extending plate 9 supported and strengthened along its lower edge by an angle bar 10 supported at a short distance inward from said wall. Within the fire chamber 4 above 45 the ash pit 3, is supported a grate bearer

11 upon which the lower ends of the inclined grate bars 12 rest, the upper ends of said bars being supported by a suitable channel iron 13 to which is secured an angle plate 14 extending along one side of the fire chamber throughout its length. The grate bars and their supports may be of any suitable well known construction.

50 A supporting structure formed of channel bars 17 forms a support for the lower ends of reciprocable feed bars 16 which extend in an inclined position across the drying and coking chamber 27 located between the open side of the fire chamber and the hopper, and the upper ends of said bars 70 are supported by similar channel bars 15 located near the wall 2 beneath the open lower end of the hopper 8. These bars are all supported at their ends upon rolls 18 so that they may be easily moved longitudinally in an approximately horizontal plane, said bars being formed at each end with a horizontally extending portion or rib 19 to engage said rolls.

55 Supported in suitable bearing brackets 80 secured to the lower side of the channel bars 15, is a rock shaft 20 and to upwardly and downwardly extending arms 21 on said shaft are pivotally attached connecting bars 22, the opposite ends of which are pivotally attached to downwardly extending lugs 23 on the feed bars 16. When the shaft 20 is rocked by any suitable means, not shown, every alternate feed bar is moved forward as the intermediate bars are moved 60 in the opposite direction and the upper edge of each bar is notched or stepped to form a series of seats for a series of pusher-blocks 24, each bar with its blocks resembling stairs in appearance, the blocks resembling the 65 stair treads. Each pusher-block is detachably attached to its bar by a pin extending through an ear 25 on the bar and a web 26 on the block. The blocks on each bar are of a length to fit loosely between the two adjacent bars and the transversely aligned blocks on the alternate bars together form ledges or shelves extending the length of the furnace and the blocks of each row or ledge being all carried by bars which are 70 moved simultaneously in the same direction, each ledge or shelf is moved forward and back as a whole. The bars are so made and the blocks secured thereon in such relative 75 positions that the rows of blocks carried by 100

105 110

one set of bars each lie between the adjacent rows of blocks carried by the other set of bars, and thus each row or ledge is moved outward as the row next above and the row 5 next below are moved inward. The blocks are of such a width that the rows overlap and thus the material upon the feeder is prevented from dropping through. The sliding of one row of blocks upon another, 10 gradually feeds the material from the hopper downward and deposits it upon the upper ends of the inclined grate bars, at the same time spreading and mixing the same as it passes downward. The refuse to be 15 burned is thus spread out in a comparatively thin layer over a large area and mixed and stirred as it is fed downward, to present every portion of it to the action of the hot products of combustion which are directed over it by the arch 5. The material is thus thoroughly dried and may, in some instances, be coked by the time it reaches 20 the grate bars. The rapidity with which it will be fed from the hopper may be regulated by the speed at which the rock shaft is 25 operated to actuate the feed-bars. The outlet 28 for the products of combustion is between the arches 5 and 6 almost opposite the opening through which the refuse enters 30 and thus a strong current of air is drawn in through the hopper, preventing the fire from burning up into the hopper and this air current following along the surface of the arch 6 mixes with the gases and aids 35 combustion without interfering with the drying and coking of the refuse.

From the outlet space 28, the products of combustion escape through a flue 29. The arch 5 being curved longitudinally of the 40 fire chamber 4 tends to direct the products of combustion toward its highest part intermediate the ends of the chamber where they pass from said chamber above the lower ends of the feed bars and out through the 45 opening between the arch 6 and the edge of the arch 5. By curving the arch 6 oppositely to the arch 5, the lower edge of said arch 6 is brought down to the mouth of the hopper and it curves upward therefrom over 50 the arch 5 causing a current of air from the hopper to flow along its inner surface where it mixes with the gases and aids combustion, then passes out through the outlet.

Having thus fully described our invention what we claim is:—

1. A furnace of the character described comprising a fire chamber open at one side and having a fire arch thereover, a hopper hav-

an open lower end supported at a distance 60 from the end of the fire arch, a second arch curving upwardly from the open lower end 65 of said hopper to a point above said fire arch with a space between said arches forming an outlet for the products of combustion, and inclined feed members extending from beneath the open lower end of the hopper to the open side of the fire chamber.

2. A furnace of the character described comprising a fire chamber open at one side and having a fire arch extending thereover, 70 a hopper supported at a distance from the open side of the fire chamber and having an open lower end extending the length of the said open side substantially in the plane of said fire arch, an arch curving upward from 75 the lower end of the hopper across the said space between the open end of the hopper and the open side of the fire chamber and extending over the fire arch at a distance above the same to form a space between said 80 arches for the passage of the products of combustion, inclined grate bars supported within the fire chamber with their upper ends adjacent to the open side of said chamber, inclined movable members extending 85 from the upper ends of the grate bars to beneath the open lower end of the hopper, and means for actuating said members.

3. In a refuse burning furnace the combination of a fire chamber having an open 90 side and provided with a fire arch extending thereover, a hopper extending the length of the fire chamber and located at a distance from the open side of said chamber, said hopper having an open lower end, and, 95 provided with an arch plate forming one side of the throat of the hopper, and provided with a seat for an arch at its lower end, an arch engaging said seat and curved upwardly therefrom and extending over the 100 fire arch with a space between said arches for the escape of the products of combustion, inclined grate bars within the fire chamber with their upper ends supported adjacent to the open side of said chamber, 105 inclined feed members extending from the upper ends of the grate bars upwardly beneath the open lower end of the hopper, and means for actuating said feed members.

In testimony whereof we affix our signatures in presence of two witnesses.

JOHN R. FORTUNE.
HAROLD S. WELLS.
